UNITED STATES PATENT OFFICE.

ELZEAR MICHAUD, OF CHICAGO, ILLINOIS.

WHISTLE.

1,324,609.

Specification of Letters Patent. Patented Dec. 9, 1919.

Application filed November 29, 1918. Serial No. 264,530.

To all whom it may concern:

Be it known that I, ELZEAR MICHAUD, a citizen of the United States, residing at Chicago, in the county of Cook and State of Illinois, have invented new and useful Improvements in Whistles, of which the following is a full, clear, concise, and exact description, reference being had to the accompanying drawing, forming a part of this specification.

My invention relates to improvements in whistles, and has for its object, the production of a device, parts of which are so arranged as to accomplish the desired results with certainty.

A further object is the production of a device embodying positive valve action and one in which the spring member is so situated as to be prevented from buckling.

20 A further object is the production of a device in which the amount of air introduced in to the resonance chamber can be varied at will.

25 A further object is the production of a device of few parts cheaply constructed and one not liable to disarrangement.

These and such other objects as may hereinafter appear are attained by the use of my block, embodiments of which are illustrated in the accompanying drawings, in which—

Figure 1 represents a front elevation of my improved device and

Fig. 2 represents an elevation showing a 35 different view of my device with the base in section.

Fig. 3 represents a horizontal sectional view on the line 3—3 of Fig. 2 looking in the direction indicated by the arrows.

40 Fig. 4 represents a bottom plan view of my device.

Fig. 5 represents a fragmentary elevation partly in section of a modified form of my device.

45 Fig. 6 represents a perspective view of Fig. 5.

Fig. 7 represents a plan view of my improved plunger.

Like numerals of reference indicate like 50 parts in the several figures of the drawings.

Referring now to the drawings—

My device comprises a metal base 7, to which is secured a metal cylinder 8, the interior of which forms the resonance

chamber of the whistle. The casting 7, has 55 a circumferential flange 9, at its lower end adapted to receive a pipe or tube 10, communicating with the source of pressure. A vertical opening 11, communicates with this source of pressure and opens into a horizontal valve chamber 12. From the extreme end of this chamber, a passage 13, communicates with a circumferential channel, 14, in the upper portion of the casting formed inside the circumferential flange 15. 60 A centrally disposed boss 17, projects upwardly from the casting and is bored to receive the retaining bolt 18, which is screw-threaded at its lower end as shown at 19. On the top of the casting 7, is a circular 70 diaphragm 20 having upwardly turning flanges 21, adapted to engage and fit snugly against the outer walls of the cylinder 8. This diaphragm is also provided with a central bore or opening 22 through which 75 the retaining bolt 18, passes.

The top of the cylinder 8, is covered with a flanged cap 23, through which the bolt 18 passes and a nut 24 is screwed on the upper end of the bolt so that by tightening this 80 nut the casting, diaphragm and cylinder top and the cylinder itself are rigidly secured together. In the lower portion of the side of the cylinder just above the diaphragm, I provide the ordinary whistle 85 mouth 25, which is slightly dished inwardly at the top as shown at 26, thus to permit the air to be deflected and consequently increase the sound.

Within the valve chamber 12, is mounted 90 a cylindrical pin or valve stem pin 27, having its end cut away forming a curved deflecting surface 28. The casing 7 is provided at one side with a projecting boss 29 having a diagonal groove 30 cut therein. A 95 connecting arm or crank pin 31 is secured to the outer end of the valve rod 22 and is arranged to travel in the groove 30. The outer face 32, of the groove acting as a cam-track for the crank pin so when it is operated to revolve the pin 27, it also moves it forward. The lever arm 33, is attached to the end of the crank pin at 34 to one arm of which 35, is secured a spring 36, the other end being connected with the spring support 37 mounted on the side of the cylindrical casing.

To the outer end of the other arm 38, is

attached a connection 39, which extends to a hand control (not shown.) The diaphragm 20, is provided with a curved slot 40 permitting communication between the resonance chamber and the chamber 14 formed in the upper portion of the casing below the diaphragm. On the upper surface of the diaphragm is mounted a sliding valve plate 41, pivotally secured to one end 10 by means of a screw member 42. The member 41, is so placed as to be concentric with the slot 40, so when the member is moved forward or back, it opens or closes the slot. It will be noted that this slot is preferably 15 placed on the side of the diaphragm opposite the inlet passage 13.

In the operation of this form of my device, when the parts are in the position indicated in Fig. 2, the round surface of the 20 valve pin 27, covers the opening 11, thus preventing the ingress of steam or pressure from the source of supply. It is held in this position by the spring 36, through its connecting members. The size of the slotted 25 opening 40, in the diaphragm has been adjusted so as to permit the entrance of the right amount of pressure and the compressed steam or air is forced in and around the chamber 14 up through the slot 40 where it 30 strikes the edge of the mouth 25, and is deflected causing the whistling noise desired. The character of the sound can be varied by varying the size of the resonance chamber, and also the amount of steam permitted to 35 enter therein through the slot 20, the area of which can be varied at will.

In the modified form of my device, illustrated in Figs. 5 and 7, the casting 7^a is formed in hexagonal form to permit the use 40 of a wrench in assembling and disassembling the parts, and certain modifications appearing in respect to the valve controlling the intake. In this form, the casting is provided with a central bore 43, in which is mounted 45 the valve pin 44, having a portion cut away as shown at 45, the cut being curved and extending possibly half way through the rod. A spring 46 is interposed between the end of the stem and an adjustable screw 47, which 50 is screwed in the end of the opening 43, thus confining the spring between the ends of the bolt 47, and the end of the valve rod. An upwardly extending ear 48, is provided and a lever, 49, mounted thereon as indicated at 55 50. The lower arm 51, of the lever, is pivotally connected at 52 with the outer end of the valve rod 44 and to the upper end of the upper member 53, is a connection 54, terminating in a hand control (not shown) same as 60 shown at 39 in Fig. 1. In this form, the pressure passes through the passage 55 and in the chamber 56, below the diaphragm and out through the opening into the resonance chamber in exactly the same manner as in 65 the preferred form, the only difference in

this construction being in the operation of the valve permitting the ingress of the air.

In the operation of this form of my device, the spring 43, presses the front rod 44, out until the end of the arm 53, strikes the 70 side of the cylinder in which position the valve is closed. When it is desired to open the valve for the purpose of whistling, the connecting rod or chain 54 is pulled forwardly forcing the valve rod 44 against the 75 pressure of the spring until the dished out portion 45, reaches the position shown in dotted lines 45. At which time a clear passage is provided from the source of steam to the whistle and the whistle continues to 80 sound so long as the connecting rod is pulled. When the pull is removed, the spring forces the rod 44 back into its position shown in full lines and closes the opening.

In the form of rod shown in Fig. 7, the 85 outer end is preferably slotted as shown at 57 although of course it is evident that the lower end of the lever 51 might be a yoke and fit over the end of the rod.

It is to be noted that the screw 47, is used 90 as an adjustment screw to regulate the tension of the spring 43, so that the valve may be kept closed under any desired tension.

Another advantage in this construction is that when the screw is out the valve rod and 95 spring may be removed and the bore cleaned of any accumulated dirt or carbon, it being simply necessary to run a brush through the bore lengthwise removing all foreign substances.

I have thus shown simple and efficient construction by means of which a serviceable whistle is produced and one in which the parts are subject to the least possible strain and one in which the most accurate results 105 may be attained. Of course, it is to be understood that it is possible to embody my invention in other forms without departing from the spirit of my invention.

It will be noted that the fact that the 110 valve stem pin 27, is given a spiral motion through the cam shaft, serves to keep the valve opening clear from carbon as the edges of the inclined surface 28, become cutting edges when they pass the opening 11, and 115 cut off any carbon that may happen to have accumulated therein.

I claim—

1. In a whistle, the combination with a supporting casting having a depression in 120 its upper face; a resonance chamber mounted thereon; a diaphragm having an opening therein interposed between said chamber and casting; means for varying the area of said opening; a source of pressure communicating with the interior of said casting below said chamber and means for controlling the amount of pressure entering therein.

2. In a whistle, the combination with a supporting casting having a depression in 130

its upper face; a resonance chamber mounted thereon; a diaphragm having an opening therein interposed between said chamber and casting; means for varying the area of 5 said opening; said means comprising a sliding member mounted on the top of said diaphragm; a source of pressure communicat-

ing with the interior of said casting below said chamber and means for controlling the amount of pressure entering said chamber. 10

In witness whereof, I have hereunto subscribed my name.

ELZEAR MICHAUD.
